Cadaulader Board of Philadelphia
Sellers Patent

The Cadaulader referred to in this Sellers Patent and making part of the same containing a description in the words of the said Cadwallader Evans himself of his improvement in the mode of applying a fusable alloy as a guard against explosions of Steam Engine and other Boilers.

To all to whom these presents shall come: Be it known that I Cadwallader Evans of the City of Philadelphia in the County of Philadelphia and State of Pennsylvania, have invented a new and useful improvement in the mode of applying a fusible alloy as a guard against explosions of Steam Engine and other Boilers, and that the following is a full and exact description of the construction and operation of the machine or apparatus invented by me for that purpose, and which is also exhibited in the accompanying drawings under two modifications thereof, the drawings appertaining to and making a part of my Specification. Fig 1. & 2. represent the same machine, the former in perspective and the latter in section, the same letters referring in each to the same parts.

A. is a tube of Brass or other metal about five inches long and about one and a quarter inch bore, and one eighth thick at its sides and bottom. B is a flanch or plate of the same metal about five inches diameter and three eighths thick. C is a valve cock projecting about one and a half inch above the flanch & about three quarters of an inch below the bottom of it: this cock has a hole thro' it of about two tenths of an inch diameter.

all the above described parts are best formed in one casting. D is a plug of brass or other metal secured into the top of the tube A. E is a round iron plug formed with it a stuffing box, within this stuffing box F is a form suitable for holding in as to exclude the air from the interior of the tube A. F is a lamp

or mass of fusible alloy that will melt at the required temperature. G is a button or piece of brass or iron, about three quarters of an inch in diameter and resting on the alloy. It is a brass or iron stem about three eighths of an inch in diameter, which is fastened to G and passes through the stuffing Box, and is screwed into the bottom of I, a weight which may be equal to thirty pounds, or more less. K is a round piece of metal of about half an inch in diameter, screwed into the top of the weight I. — L is a handle for the purpose of raising the weight when required. M is a guard placed about the top of the weight and about a quarter of an inch above it. When the weight is supported by the piece G as it rests on the alloy, the top of the guard should be about half an inch below the bottom of the handle L, so that when the alloy melts, the weight will descend until the handle will rest on the guard; this guard is also intended to keep the weight in its upright position by means of the round iron piece K, passing thru. a hole in the centre of said guard. N.N. are two Rods about half an inch in diameter which are fastened to the flange B, and are of sufficient length to support the guard M. O is a small valve fitted to the bottom of the valve cock, to this valve is secured a small stem which passes thru the cock and extends up to within about a quarter of an inch of the bottom of the weight; in the top of this stem is a button of metal P, which may be about half an inch in diameter. Q is a spiral spring for the purpose of keeping the valve up to its place. R represents the top of the boiler to which the apparatus is bolted, with the tube A containing the fusible alloy, projecting into the interior of the Boiler. so also does the lower end of the valve cock, as seen at O.

The operation of the above described apparatus is as follows. The fusible alloy T is so made as to melt at a temperature a little above the regular working temperature of the steam in the Boiler. that is to say if in a high pressure boiler the safety

50

value is made to operate at a hundred and fifty pounds pressure on the square inch. The alloy should fuse at a temperature corresponding to about one hundred and sixty pounds. and in a low pressure or condensing engine supposing it calculated to work at a pressure of ten or fifteen pounds. the alloy should fuse at a temperature corresponding thereto say at about fourteen or nineteen pounds. — When the temperature of the steam in the Boiler is such as to fuse the alloy. the piece C descends, into it and allows the weight to fall upon the top of the stem P. which forces open the valve O. and lets the steam escape up thro' the valve cock which it will do with considerable noise. and the attention of the Engineer will thus be called to the increased temperature of the boiler. which may be caused either by the ^{prolonging of the} steam being too high or the water therein being too low.

The Engineer will then proceed to examine the safety valve to see that it works freely, and the gauge cocks to try the height of the water. he will then know from which of the two causes the alloy has fused, and proceed to correct the evil. It may however so happen on board of Steam Boats, that the gauge cocks, will show plenty of water and the safety valve be not overloaded altho' the alloy has fused; in that case it would appear that the boilers were not level. and that some part of the back end of them was acted on by the fire without having water in contact with it.

It would on this account be advisable to place two of the above described apparatus, on each Boiler. one to contain an alloy fusible as above. the other an alloy that will melt at a temperature a little higher. so that the Engineer may know. whether the temperature of the Boiler is increasing or not; for should the alloy fuse in the second apparatus also he will then know that he has not been able to correct the evil and must therefore put out the fire. The above described apparatus ought to be enclosed in a cast iron or other metallic cover under lock and key so that the Engineer cannot get at it the key being kept by the Captain.

May 8, 1834

or other person whose duty it will be to raise the weight when the apparatus has gone into operation and to place the forged piece *S* between the guard and the handle so that the alloy may conceal in its place, and be ready for another operation. The fork is then to be removed and the box locked. Fig 3 represents a sectional view of another modification of this machine and fig 4 is a front view of it as it appears on the outside of the box or head.

A is a hollow metallic cylinder, the interior of which is about one inch long and about two inches in diameter, and it may be about one eighth of an inch thick. *B* is a round part of the same piece of metal about two and half inches long connecting the cylinder to the flange *C*, which is about five inches in diameter and three eighths thick. The interior of *B* is in the form of the frustum of a cone, the base of which joins the cylinder *A*, the diameter being about one inch and extending towards the flange about one and a quarter inch where it is about three quarters of an inch in diameter. This part of the interior of *B* is made conical for the purpose of preventing the alloy which is placed in *A* from getting towards the flange. The above described form of the interior of *A* + *B* may be given to it in casting by means of a core, and that part which forms the hole through which the shaft *D* passes may be drilled as also may the cavity to receive the plug *E*, and form the stuffing box *F*, in a valve rock similar to that in the first described apparatus. *G* is a small lever the arms of which are at right angles to each other one laying across and a little above the lever *H*, the other standing upright and having the stem of the valve *I*, passing thro' it on this stem are screwed two small round pieces of metal about half an inch in diameter, one of them being placed between the small lever and the flange, and the other on the opposite side of the lever. The one on the side next the flange is to receive the pressure of the lever to open the valve, the other is to shut it, as the back of the small lever presses against it.

when the alloy is melted, so at that time the lever H does not touch it. The lever H is enlarged at that part where the shaft passes thro' it, and has on a long slot cast into it to receive the ratchet wheel K. This ratchet wheel is fastened ^{to} and prevents from turning on the shaft by means of a square on the shaft which is between the two chucks or sides of the lever H.

L. is a ratchet or pawl which catches in the teeth of the ratchet wheel and causes the shaft to turn with it when the alloy has fused. about four inches from the shaft on the lever H. is fastened the weight M. which may weigh about eight pounds.

On and near the end of the shaft which is in the cylinder A. I place an arm O. of brass or iron, one and three quarters of an inch long & three eighths square. this arm should be first made and then moulded in the core that forms the interior of A. N. is a plug of brass or iron screwed into the cylinder A. in this plug is formed a place for the journal of the shaft to work in. the hole in which the plug is screwed is also for the purpose of getting at the arm, to put it on the shaft. The shaft may be made to extend to the casing P. and the valve stem may be made to extend to and pass thro' the casing. as shown in the drawing, in that case the valve cock can be used at all times as a common gauge cock. Q is a fusible alloy placed in the cylinder A. The deviation from a true cylinder as shown at R. is for the purpose of preventing the alloy from freezing in the cylinder. S is the Boiler head. T. T. are the screw bolts that secure the fixture to the boiler head. A. B. and the valve end of cock, are the parts of this apparatus which projects into the boiler. The operation of the machine as thus modified is as follows. When the alloy fuses. the arm O being no longer supported or prevented from turning the weight is allowed to descend which causes the lever H. to press against the small lever G. this causes the upright end of said lever to press against the small brass pin in the valve stem, which forces open the valve I. and allows the steam to escape. and the engine receives no

as in the first described apparatus. In this modification of the machine it makes no difference whether the alloy congeals around the arm in the cylinder or not, as it can be set for another operation at any time; for should the metal become hard while the arm is in it, it will only be necessary to raise the weight, and the ratchet will take a new hold on the rotated wheel.

Of how thus described two methods, by which I intend to carry my improvement in the mode of applying fusible alloy, in effect, which improvement I do hereby declare consists in the employment of an unlighted tube or vessel to contain the alloy by which it will be preserved from oxidation or waste for a great length of time, and in which it can be used many times in succession for indicating a certain elevation of temperature without the necessity of removing it, avoiding thereby the inconvenience and danger incident to the mode hitherto practised in the employment of it. I therefore claim the use of such alloy in the manner upon the principle herein set forth whether the same be effected by means of instruments constructed exactly in the form described or in any other in which a similar effect is produced by analogous means.
